of PA (US)

(57) **CLAIM**

The ornamental design for a playard with inwardly curving legs, as shown and described.

(73) Assignee: **Graco Children's Products Inc.**,
Elverson, PA (US)

DESCRIPTION

(**) Term: **14 Years**

FIG. 1 is a perspective view showing the playard with inwardly curving legs of our new design;

(21) Appl. No.: **29/141,543**

FIG. 2 is a top plan view thereof;

(22) Filed: **May 9, 2001**

FIG. 3 is a bottom plan view thereof;

(51) LOC (7) Cl. **06-01**

FIG. 4 is a left side elevation view thereof, the right side elevation view being a mirror image of the left side elevation view;

(52) U.S. Cl. **D6/331; D6/391**

FIG. 5 is a front elevation view thereof, the rear elevation view being a mirror image of the front elevation view;

(58) Field of Search D6/382, 390, 391,
D6/331, 503; 5/93.1, 93.2, 100, 101

FIG. 6 is a partial cross-section view thereof, taken along line 6—6 of FIG. 4, to more clearly show the inside thereof; and,

FIG. 7 is a partial cross-section view thereof, taken along line 7—7 of FIG. 5, to more clearly show the inside thereof.

The broken lines are for illustrative purposes only and do not form part of the claimed design.
